SCALE PIVOT

Edward J. Von Pein, Dayton, Ohio, assignor, by
mesne assignments, to International Business
Machines Corporation, New York, N. Y., a cor-
poration of New York

Application February 28, 1931, Serial No. 518,928

9 Claims. (Cl. 308—2)

This case relates to weighing scales and particularly to the pivot members thereof which serve as the fulcrums of the levers and other scale parts.

5 The object of the invention is to provide novel means whereby a scale pivot will be easily attachable to a scale member and rigidly held in position after adjustment.

Still further the object is to provide an adjusting means for the pivot which is made separately from the pivot but is permanently attachable to the pivot before or after assembly of the latter on a scale part.

Various other objects and advantages of my 15 invention will be obvious from the following particular description of one form of mechanism embodying the invention or from an inspection of the accompanying drawing; and the invention also constitutes certain new and novel features 20 of construction and combination of parts herein-after set forth and claimed.

In the drawing:

Fig. 1 is a top view of a lever end with a knife edge pivot and its holding member in position.

25 Fig. 2 is a side view of the structure shown in Fig. 1.

Fig. 3 is a top view of the holding plate and knife edge with parts in section.

Fig. 4 is a detail of the adjusting and holding 30 plate.

It is understood that the invention is applicable to any part of a scale which requires a knife edge or other type pivot. For purposes of the present disclosure the invention has been shown as applied to a lever having a bifurcated end.

In detail, 10 is a lever having its end bifurcated to provide furcations 11 and 12. These furcations have round holes in which are fitted the round ends 13 and 14 of the knife edge pivot 15. The 40 round end 14 has an extension 16 which has two parallel flat sides 17 and two round sides 18 which are continuations of the round end 14. The extension 16 is adapted to fit within the hole or slot 19 adjacent one end of a plate member 20 which 45 at the other end has a vertically disposed elongated slot 21 through which a screw 22 may be inserted and threaded into a hole in the adjacent furcation 12. It is seen that the head of screw 22 retains the plate 20 on the outside of 50 furcation 12. When the screw 22 is loosened the plate 20 may be adjusted pivotally about the center of the round ends 13 and 14 of knife edge pivot 15. This movement results in a rotative adjustment of the knife edge pivot 15 about its 55 round ends so that the knife edge apex is proper-

ly positioned with respect to the other pivots of the lever or as desired. The plate 20 is of softer metal than the pivot 15. The rounded ends 18 of pivot extension 16 have grooves 23 formed therein. After the plate 20 is positioned on the extension 16 the metal of the adjacent walls of slot 19 is pressed into grooves 23 by any suitable tool. This may be done by staking the metal of plate 20 about the hole 19 into the grooves 23 of the pivot. As a result of the metal flowing 60 into grooves 23, the extension 16 and walls of slot 19 are in effect permanently and integrally secured to each other, thus providing a substantially integral knife edge pivot and adjustment plate therefor. The staking operation on the plate 20 may be made before the knife edge is 65 inserted into the holes of the lever 10 or may be made after the pivot is placed within said holes and the adjusting plate 20 subsequently attached to the lever.

70 While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following 75 claims:

1. In a scale, a pivot element having a V-bearing portion and a round portion, a carrier for rotatably receiving the round portion, a plate-like member extending transverse to the axis of the element and adjustably secured to the carrier, said member and element being rigidly secured to each other, adjustment of said member relative to the carrier being about the pivot element axis to angularly adjust the V-bearing portion. 90

2. In a scale, a knife edge pivot element, a carrier therefor, an extension on the element projecting past the carrier, said extension having a groove, and a member provided on the carrier 100 and having an opening receiving the extension and adapted to have the metal of said opening forced into said groove whereby the pivot element and the member may be permanently attached to each other. 105

3. In a scale, a knife edge scale type pivot of hard metal, a holding member for the pivot of softer metal than the pivot, said pivot having grooves, said member having portions adjacent 110 said grooves which are adapted to be forced into

the grooves to effect a permanent connection between the member and the pivot, a scale member for carrying the assembly of pivot and holding member, and means for holding the latter stationary relative to the scale member.

4. In a scale a knife edge scale type pivot element, a holder therefor, the pivot element having grooved portions, the holder having portions adjacent said grooves which are adapted to be forced into the grooves to permanently connect the holder and pivot, and a scale lever having means for carrying the holder and pivot, the holder extending transversely to the axis of the pivot and comprising a plate-like element substantially flat against the side of said carrier, means for adjustably securing the holder in position on the carrier.

5. In a scale, a lever, a unitary assembly carried by the lever, the assembly being comprised of a separately formed knife edge bearing element and a separately formed plate extending substantially at right angles to the knife edge and permanently rigidly, non-adjustably, and substantially integrally secured to said element and means for securing the plate to the lever, said assembly being removable as a rigid unit from the lever.

6. In a scale, a scale bearing having a V-shaped bearing portion, a carrier for the bearing, a member secured to the carrier, and a connection between the member and bearing of a nature to provide a permanent, rigid, non-adjustable, and

substantially integral bond between the bearing and said member to hold the bearing stationary relative to the carrier.

7. In a scale, a scale bearing having a bearing surface for supporting a V-shaped scale pivot, a carrier, a member having a portion abutting a portion of the bearing, a staked connection between the abutting portions of the bearing and member to rigidly connect the member to the bearing, and means for securing the member to the carrier and retaining the member stationary relative to the carrier to hold the bearing in position on the carrier.

8. In a scale, a scale bearing having a bearing surface for supporting a V-shaped scale pivot, a lever, a member having a portion abutting a portion of the bearing, a staked connection between the abutting portions of the bearing and member to rigidly and in effect integrally connect the bearing and member, and means for mounting the member on the lever to hold the bearing stationary relative to the lever.

9. In a scale, a scale bearing having a V-shaped bearing portion, a carrier, a member secured to the carrier and of softer material than the bearing, and a rigid connection between the member and bearing comprising metal of the member spread into interlocking relation with said bearing to maintain the bearing stationary relative to the carrier.
